[57] CLAIM

The ornamental design for a golfer's aiming aid for a tee, as shown and described.

DESCRIPTION

FIG. 1 is a side elevational view of a golfer's aiming aid for a tee showing my new design, the opposite side elevational view being a mirror image thereof.

FIG. 2 is a top plan view thereof;

FIG. 3 is a bottom plan view thereof, rotated 180° from its FIG. 1 position.

FIG. 4 is a front elevational view thereof.

FIG. 5 is a rear elevational view thereof.
